UNITED STATES PATENT OFFICE.

JOSIAH JOWITT, OF STANLEY, NEW JERSEY.

APPARATUS FOR MAKING ROOFING-FELT AND SIMILAR FABRICS.

SPECIFICATION forming part of Letters Patent No. 291,600, dated January 8, 1884.

Application filed April 3, 1883. (No model.)

To all whom it may concern:

Be it known that I, JOSIAH JOWITT, a citizen of the United States, residing at Stanley, in the county of Morris and State of New Jersey, have invented certain Improvements in Apparatus for Making Roofing-Felt and other Similar Fabrics, of which the following is a specification.

My improved apparatus is designed chiefly for the manufacture of three-ply roofing-felt from tarred paper, but it is also applicable to the treating or saturating of single webs or thicknesses of paper or other fabrics with tar, pitch, or other substances, and to the manufacture of two-ply building or roofing paper. It is in the main an improvement on the machine illustrated in my application, No. 80,566, filed December 30, 1882.

Figure 1 of the accompanying drawings is a side elevation of my improved machine employed for the manufacture of three-ply felt. Fig. 2 is a plan thereof. Fig. 3 is a vertical longitudinal mid-section thereof. Fig. 4 is a fragmentary plan, showing the winding-roll. Fig. 5 is a vertical section of this roll, cut in the plane of the line 5 5 in Fig. 4. Fig. 6 is a similar view to Fig. 3, showing the machine arranged for making two-ply felt; and Fig. 7 is a similar view, showing a modified construction.

Referring first to Figs. 1 to 3, let A A designate the fixed frame-work of the machine, providing suitable bearings for the rotating parts.

B is the tank containing the tar, pitch, or other substance with which the paper or other fabric is to be treated.

C is a steam-coil in said tank, or other means of heating the contents thereof.

D D are hollow pressure-rolls, heated by the introduction of steam to their interiors, geared together, and driven by power, and E is a drying-cylinder, which is also heated by steam and driven by power. There may be one or more cylinders E.

F is a roll of paper or other fabric, which is to form the middle or inner layer of the three-ply felt, and G' and G² are two other rolls of paper, which are to form the outer layers of the felt. The web of fabric a a from the roll F is carried over a series of dandy-rolls, c c, to give it the requisite tension, de-

scends thence into the liquid in the tank B, and passes around a roller, d, which is immersed therein, ascends thence to and passes between the rolls D D, passes thence over the drying-cylinder E, thence around a fixed or non-rotative steam roller or pipe, e, and extends thence to the winding-roll H. The web of fabric d' from the roll G' passes over dandy or tension rolls f f, thence around a steam-roller, g, and thence to the winding-roll H. The web d² from the roll G² passes over a roller, I, revolving in a tank or trough, i, passes thence around a steam-roller, h, thence in nearly horizontal direction to and around a steam-roller, h', and thence to the winding-roll H.

In making three-ply roofing-felt, three rolls of felt paper are first treated independently, to make them water and weather proof, by passing each one through this machine, or a similar one, in the same manner as the web a a in Fig. 3. Coal-tar is placed in the tank B, and is heated by the steam-coil C. As the fabric passes through the hot tar it becomes saturated therewith, and in passing between the hot pressure-rolls D D and over the cylinder E (of which there should be several) it becomes thoroughly dried. This treatment is more fully described in the patent of George S. Page, 75 granted July 20, 1880, No. 230,148. The three rolls having thus been saturated with tar, they are combined into three-ply felt by placing them in the machine, as shown, and winding all three webs upon the winding-roll H together. Coal-tar pitch is placed in the tank B and heated, and the inner web, a, is passed through it, and thereby coated with the pitch, and the three webs are rolled together while this pitch is still warm and adhesive, whereby the inner web is cemented to both the outer ones. This process is more fully described in my application for patent on "improvements in roofing-felt and its manufacture," executed simultaneously herewith.

Heretofore the roofing-felt or other fabric has been wound up on a metal shaft set in bearings in the machine. The end of the web or strip was secured to this shaft by being pressed, by means of a rod, into a longitudinal groove in the shaft, and it was then wound up by applying power to rotate the shaft, and when sufficient material was then wound upon the roll the shaft was removed from its bear-

ings and withdrawn from the roll by pulling it out longitudinally, after first drawing out the rod. The cavity thus left in the roll was then filled by driving in a wooden roller, in order that the roll should not be collapsed by the pressure applied to it in storage and transit. These operations of removing and replacing the shaft on the machine, of withdrawing the shaft from the rolls, and of driving the wooden rollers into the rolls are difficult and laborious, and entail considerable expense upon the manufacturer, and the fabric is crimped or corrugated at intervals for a considerable distance from its inner end by passing over the groove-and-rod fastening, thereby rendering this portion of the roll useless and a waste to the consumer. To obviate these defects I have designed the improved construction of winding-roll shown in Figs. 4 and 5. Two short shafts, *J* and *J'*, are mounted in long bearings on the two side frames of the machine, one shaft being in each bearing, and both being in the same axial line. The shaft *J* is confined by collars or shoulders, so that it cannot move endwise, and has fixed on it a belt-pulley, *K*, or a gear, or other means by which power may be applied to rotate it. The shaft *J'* is capable of sliding longitudinally a short distance in its bearing, and is operated by a lever, *L*, to which is pivoted a collar, *l*, which enters between shoulders on the shaft, and remains stationary while the shaft rotates within it. The shaft is shown slid to the left in Fig. 4, and to the right in Fig. 5. In either position it is held by locking the lever to a curved arm, *k*, by inserting a pin through coinciding holes in the lever and arm, or by any suitable lock or latch. The ends of the shafts *J* *J'* which are nearest each other are formed into cups or sockets *j* *j'*, and are separated to a distance at least equaling the width of the material to be made on the machine.

M is a bar or roller, preferably of wood, the ends of which fit into the cups *j* *j'*, and which is or may be a counterpart of those heretofore used to drive into the finished roll. Before commencing to wind up a roll, the shaft *J'* is moved to the position shown in Fig. 5, a roller, *M*, is inserted at one end in the cup *j*, and the shaft *J'* is moved to the left until its cup *j'* incloses the other end of the roller, and the latter is tightly clamped longitudinally between the two shafts. To prevent the turning of the roller ends in the cups, the latter are provided with teeth which engage and indent the wood. Upon power being applied to turn the shaft *J*, the roller *M* and the shaft *J'* turn with it, and by attaching the end of the felt or other fabric to the roller *M* it will be wound thereon. This attachment is effected by simply rolling the end of the felt around the roller, until it is caught under the web, when the friction becomes sufficient to insure its rolling up. I thus dispense with the complicated and troublesome groove and rod heretofore used, and avoid the crimping of the fabric near the

end of the roll, which results from the use of that fastening, and which renders the end portion of the fabric unfit for use. When the entire roll is wound upon the roller *M*, the rotation is stopped, the shaft *J'* moved to the right, and the roller *M* taken out of the machine. The roll is then ready for use or sale. Another roller *M* is placed in the machine, and the operation proceeds. The shaft *J'* may also have power applied to rotate it, if necessary, or it may be non-rotative, and the roller *M* may rotate in the cup *j'*. Instead of cups *j* *j'*, points or spurs may be used; but I prefer cups, because they insure the correct centering of the roller *M*.
70 75 80

The above-described device is very similar to that commonly employed in winding cloth and ribbons.

The most important feature of my invention 85 consists of the steam-rollers *g* and *h*, over which the outer webs, *b* *b'*, pass, and by which these webs are heated before they come in contact with the middle web, *a*, which has received the coating of pitch. By thus heating the 90 outer webs they are prevented from chilling the pitch, and the latter is kept warm and adhesive, so that the thorough cementation of the three webs is assured. Heretofore only the inner web has been heated, and in cold 95 weather difficulty is often experienced in keeping the coating of pitch warm enough to be sufficiently adhesive. The roller *h*' may be a steam-roller in place of or in addition to the roller *h*.

In laying roofing-felt it is customary for the 100 roofers to paint it after it is in place, and then sand it upon the fresh paint. This is an operation of some difficulty, and I therefore propose to paint and sand the felt during the manufacture. For this purpose I have provided mechanism for applying paint and sand to the web *b'*, which is the one that is rolled up toward the center of the roll. This mechanism is best shown in Fig. 3. The roller *I* and tank *i*, already referred to, constitute the 110 painting device. The paint, varnish, cement, or other material employed is placed in the tank *i*, and the roller *I* takes it up and applies it to the surface of the web *b'*. In passing around the steam-roller *h*, this paint is partially dried, but still remains somewhat adhesive. With some kinds of paint it may be preferable to not heat the roller *h*. From this roller the web passes nearly horizontally to the roller *h*', and in so doing a layer of sand is 115 sifted upon it from a sieve or screen, *N*. This sieve is vibrated or agitated by any suitable mechanism—such as a crank and pitman—which I have not thought it necessary to show. A portion of the sand adheres to the freshly-painted surface, and the remainder drops off while the fabric is bending around the roller *h*', and falls into a trough, *m*, placed beneath this roller. Thus all superfluous sand is removed.
120 125 130

In making two-ply felt it is preferable to sand the web *b*, which joins the web *a* from

below, as shown in Fig. 6, in which case the winding-roll should revolve in the opposite direction. The web *b* winds off the roll *G*, extends to the roller *f*, thence back over the printing-roller *I* to the roller *f'*, thence horizontally beneath the sanding-sieve *N* to the steam-roller *g*, and thence to the winding-roll, the sanded surface in this last excursion being inverted, so that the excess of sand drops off into the sieve or onto the portion of the web beneath.

In making two-ply felt I do not pass the web *a* through a bath of pitch, but apply the pitch to one side only, in the manner shown in Fig. 6. A tank, *p*, (shown best in Figs. 1 and 2,) is fixed on the machine, and when two-ply felt is to be made a roller, *P*, is placed in bearings formed on or above this tank, and the pitch is placed in the tank and suitably heated. As the web *a* passes over this roller, after having first been heated by the rolls *D* *D*, it causes the roller to rotate in the tank and carry up a coating of pitch, which is thus transferred to the web. The web then passes over the cylinder *E* and joins the web *b*, the two being cemented together by the intervening coating of pitch. I thus make one machine serve for making either two or three-ply fabrics.

Fig. 7 shows a modified machine arranged for making two-ply sanded felt, the sand being applied to the upper web, *a*. This web, after leaving the cylinder *E* and roller *e*, passes under a revolving printing-roller, *I*, which forms the bottom of a tank or vessel, *i*, containing the paint. Passing beyond this, the web receives a sprinkling of sand from a sieve, *N*, and beyond this sieve it passes under a rotary brush, *Q*, which sweeps off the loose sand and throws the latter back toward the sieve.

I am aware that machines have been proposed for applying an adhesive substance to a passing strip of paper, and then sand to this; and I do not broadly claim the herein-described means for painting and sanding.

I claim as my invention—

1. In a machine for making roofing-felt and similar fabrics, the combination, with the means for applying a coating of hot pitch or other cementing substance to a web or layer, and for partially drying the same, of a steam-heated roller or rollers, over which one or more other webs are passed before being rolled into contact with the coated web or layer, whereby the coating of pitch is rendered warm and adhesive, and the thorough cementation of the webs or layers is effected, substantially as set forth.

2. The combination, in a machine for making roofing-felt and similar fabrics, of the tank *B* and its roller *d*, the steam-heated rollers *D* *D*, the roller or drum *E*, for partially drying the coated web, and the steam-heated rollers *g* and *h*, for warming the exterior webs before they are brought into contact with the coated web, all arranged to operate substantially as set forth.

3. The combination, in a machine for making roofing-felt and similar fabrics, of the means described for applying pitch or other cementing material to one web, the steam-heated rollers for partially drying the said cement, the means described for applying paint to the exterior face of one web, the means described for applying sand to the painted surface of said web, and the steam-heated roller for heating or warming the other or non-coated web before it is brought into contact with the cement on the coated web, all arranged to operate substantially as set forth.

In witness whereof I have hereunto signed my name in the presence of two subscribing witnesses.

JOSIAH JOWITT.
